UNITED STATES PATENT OFFICE.

WILLIAM L. CARD, OF MOBERLY, ASSIGNOR TO THE CARD AUTOMATIC BRAKE COMPANY, OF ST. LOUIS, MISSOURI.

STEAM-BRAKE.

SPECIFICATION forming part of Letters Patent No. 224,145, dated February 3, 1880.

Application filed October 22, 1879.

To all whom it may concern:

Be it known that I, WILLIAM L. CARD, of Moberly, in the county of Randolph and State of Missouri, have invented a certain new and useful Improvement in Steam-Brakes, of which the following is a full, clear, and exact description, reference being had to the accompanying drawings, forming part of this specification.

This is an improvement on my invention described in Letters Patent No. 212,439, granted to myself, S. Watts, and E. E. Chase, and dated February 18, 1879.

In my former invention each brake-block was worked by its own proper piston in a cylinder common to both. The cylinder was made fast to a supporting plate or bracket rigidly attached to the locomotive-frame, so that the cylinder was fixed in position. The brake-blocks were supported on link-bars in such a manner that they would move upward and outward as they approached the wheels, so that there was necessarily a joint-connection between the piston and the push rod or bar connecting it with the block.

In my present improvement this push rod or bar is entirely dispensed with.

Furthermore, in case one block should come in contact with its wheel before the other one (in consequence of different amount of friction of the pistons in their cylinders or from other cause) the attachment of the cylinder and supporting-bracket would be strained.

The construction is also simplified and cheapened to quite an extent by dispensing with not only the push-rods, but by dispensing, also, with one piston on each side of the engine, with its packing-rings, thereby cheapening its maintenance as well as its construction.

This improvement overcomes the above difficulties by the use of a single cylinder supported in such a manner as to admit of sufficient vertical, longitudinal, and other movements to avoid strains incident not only to the foregoing causes, but also to curvatures of track, as no cause whatever can by any possibility throw the centers of the brake apparatus out of line. In this construction one of the brake-blocks is connected directly to the cylinder, and the other block to the piston working in the cylinder.

The movable nature of the cylinder necessitates a flexible steam-connection or some equivalent device in lieu thereof.

In the drawings, Figure 1 is a side view of part of a locomotive, showing the improvement. Fig. 2 is an enlarged top view of the cylinder operating the tender-brake. Fig. 3 is a transverse section of the bracket-plate at *a b*, Fig. 1. Fig. 4 is an enlarged detail, showing the manner of supporting the brake cylinder. Fig. 5 is a longitudinal section on *c d*, Fig. 6, of the slide-valve of the brake-operating cylinders. Fig. 6 is a transverse section of valve at *e f*, Fig. 3. Fig. 7 is an enlarged longitudinal section of the locomotive-brake-operating cylinder at *g h*, Fig. 3, but showing a modification of the device for adjustable rest for the lower end of the brake-block.

A A are the drive-wheels (upon one side) of the locomotive *B*. The brakes are applied to both these wheels and simultaneously to the driving-wheels upon the other side, the steam-pipe *S* extending over the locomotive to the operating-cylinders of both brakes, with which it connects by flexible pipe-sections *S'*.

The brakes of the tender are applied by means of steam passing through the pipe *S*, extending to steam-cylinder *H* beneath the cab.

D is a steam-chest in communication with the steam-space of the boiler, the steam entering the chest through the orifice *E*. Within the steam-chest works a *D* slide-valve, *F*, operated by a hand-lever, *G*, connected to the valve-stem *F'*.

S is a steam-pipe leading directly from the live-steam pipe *S* to the steam-chest through the central port, *s*.

The steam-port *s'* in the valve-seat communicates with the pipe *S*, through which steam enters and discharges from the cylinder *H*, through which the tender-brakes are operated.

The cylinder *H* is secured to the bottom of the foot-board *H'* by means of a stud or bracket, *H*, whose pin *h* extends through a lug, *H*, at the closed end of the cylinder, the construction allowing the engine to oscillate in a horizontal plane. The pin has a head, *h*, giving vertical support to that end of the cylinder.

The open end of the cylinder may be supported on a rod or stirrup extending beneath

it, and whose ends are attached to the foot-board.

The movable character of the cylinder requires a flexible connection with the steam-pipe S^2 . Such connection is shown at S^3 .

The piston I is connected by joint i to the lever J, fulcrumed at j to a stud or pin, J' , fixed to the bottom of the foot-board H' . The lever is connected at the outer end by means 10 of a spring, K, to the cylinder, so as to draw back the piston into the cylinder when the steam has exhausted from the cylinder.

It will be seen that the connection of the piston with the lever J will give an oscillatory movement to the piston and cylinder on the pin h . Hence the necessity for the support of the cylinder in such a manner as to permit of its oscillation.

The inner end of the lever J (where the chain L is attached) is at or about the medial of the locomotive, so that curves in the track will not materially affect the chain-connection L between the locomotive and the tender, the connection of the other end of the chain with 25 the brake mechanism of the tender being also made at or about the medial line, for the same reason.

The chain L may connect with any ordinary system of brake-levers. These are too 30 well known to need description.

s' is the exhaust-port of the valve-seat. This port is in communication with the exhaust-steam pipe S^4 .

f is a small hole through the valve F, supplying steam in small quantities to the brake-cylinders in advance of the main supply when the ports $s^2 s$ are thrown wide open.

By this device the brakes may be set on slowly, while by a full movement of the valve 40 the brakes may be applied with full force at once.

It will be seen that the location of the valve-ports is such that the brakes may be set one at a time and taken off in the same manner.

To accomplish this with an ordinary valve it is necessary that both the steam-ports $s^2 s$ should be at one side of the exhaust-port s' , thus differing from the construction of slide-valve seats of steam-engines where the exhaust-port is at 50 the middle, between the two steam-ports.

The upper and lower frames of the locomotive are shown at M M, and to these is attached the bracket-plate N, having at the upper end the stud or pin o, upon which are hung 55 the links P P, whose lower ends have joint-connection with the brake-blocks Q Q'. The lower end of the plate N has an upturned flange, n, forming a transverse guide to the steam-cylinder R by means of a bracket, r, upon the inside of the cylinder, which engages over the top of the flange or guide n. The flange n and bracket r also serve to assist in the support of the cylinder when in its lower position—that is, when the brakes are 60 off. Between the top of the flange or guide n and the bracket r, I interpose a gib, r', upon

which bears the point of a set-screw, r^2 , screwing through the bracket. An important office of the said bracket r and guide-flange n is to prevent any possibility of the brake-blocks 70 swinging outside of the tread of the wheels, while at the same time sufficient play is allowed for all lateral motion incident to curvatures of tracks, &c.

R' is an arm extending from the closed end 75 of the cylinder R, and having joint-connection at T with the brake-block Q.

R² is a downward extension of the arm R', through which passes a set-screw, R³, whose point forms a rest for the lower end of the 80 brake-block when the brake is off, and thus prevents the top of the block from resting against the wheel at its upper end. The piston U has an arm, U', similar in all respects to the arm R', and connected to the other 85 brake-block, Q', by joint t, and giving a similar lever-bearing to the block Q' by extension U² and set-screw U³.

V V are set-screws screwing in lugs of the 90 brake-cylinders, and whose points receive the impact of the outturned flange of the piston, to regulate the inward movement of the piston in the cylinder, and, consequently, the distance the brake-blocks fall back from the wheel.

At Fig. 7 is shown a modification of the adjustable back rest of the lower end of the 95 brake-block. In this modification extensions P' of the links P are substituted for the extensions R² and U² of the cylinder and piston, respectively, the set-screws P² being screwed through such extensions P', and acting in similar manner to those R³ and U³.

I claim as my invention—

1. The combination of the two brake-blocks 105 Q Q', attached, respectively, to the cylinder R and piston U, for the purpose set forth.

2. The combination, with the brake-cylinder R, of adjustable support r n, for the purpose set forth.

3. The combination of supporting-plate N with bracket-flange n, cylinder R, bracket r, and adjustable bearing r r², substantially as set forth.

4. The combination of the cylinder R and 115 piston U with bearing-arms R² and U², and set-screws R³ and U³, and brake-blocks Q Q', for the purpose set forth.

5. In combination with the brake-cylinders H and R, valve F, and valve-rod F', the seat 120 of said valve, having steam-ports $s^2 s$ and exhaust-ports s' , located and operating substantially as set forth.

6. The combination of the cylinder and piston H I, connected to the locomotive by pivot 125 h, and connected to lever J, carrying brake-chain L and return-spring K, substantially as and for the purpose set forth.

WILLIAM L. CARD.
